(57) **CLAIM**

The ornamental design for a gaming board, as shown and described.

DESCRIPTION

FIG. 1 is a front perspective view of a gaming board showing my new design;

FIG. 2 is a top plan view thereof;

FIG. 3 is a bottom plan view thereof;

FIG. 4 is a left side elevational view thereof;

FIG. 5 is a right side elevational view thereof; and,

FIG. 6 is a front perspective view thereof, shown without a supporting structure.

In the drawings, the broken lines depict portions of the gaming board that form no part of the claimed design.
